UNITED STATES PATENT OFFICE

FRANK I. STILES, OF COCOANUT GROVE, FLORIDA.

BOAT.

1,371,986.

Specification of Letters Patent. Patented Mar. 15, 1921.

Application filed August 22, 1919. Serial No. 319,162.

To all whom it may concern:

Be it known that I, FRANK I. STILES, a citizen of the United States, residing at Cocoanut Grove, in the county of Dade and

5 State of Florida, have invented new and useful Improvements in Boats, of which the following is a specification.

One object of my present invention is the provision of a boat constructed with a view 10 to enabling a person or persons carried thereby to see for a considerable distance below the surface of the body of water in which the boat is movable.

Another object of the invention is the provision of a boat having the capacity of function stated, and also having means whereby waves or rough water are prevented from interfering with the view in the water.

20 Other objects and practical advantages of the invention will be fully understood from the following description and claims when the same are read in connection with the drawings, accompanying and forming 25 part of this specification, in which:

Figure 1 is a side elevation of the boat constituting the best practical embodiment of my invention of which I am cognizant.

Fig. 2 is a plan of the same.

30 Fig. 3 is a longitudinal vertical section of the boat.

Fig. 4 is an enlarged detail section illustrative of the provision for admitting air to and practically excluding light from the 35 cabin of the boat.

Fig. 5 is an enlarged detail section illustrative of the adjustable capacity of the several rakes of the boat. The said rakes being designed to serve in preventing waves 40 and rough water from interfering with the observation through the opening in the floor of the cabin.

Similar numerals of reference designate corresponding parts in all of the views of 45 the drawings.

The hull 1 of the boat is preferably designed to be propelled through the medium of a stern wheel 2, driven by an internal combustion engine 3'. The said hull 1 is 50 formed of two pontoons or hollow bodies 4 arranged in longitudinal spaced relation, and a deck 5 which extends between and is fixed with respect to the pontoons. The inner or opposed walls 6 of the pontoons are 55 straight, and formed between the said walls 6 and under the deck 5 is a longitudinal cen-

tral channel 7 of the proportional width illustrated, and extending throughout the length of the hull and open at its forward and rear ends.

60 Superimposed upon the deck 5 is a cabin 8, and formed in the deck 5 which constitutes the floor of the cabin, is an observation opening 9, coincident with the channel 7, which opening, as its name imports, is designed to enable a person or persons within the cabin 8 to see downwardly in the water for a considerable distance. From this it follows that a person or persons within the cabin 8 are enabled to see and study the vegetation on the bottom of a body of water where the water is not too deep, and are also enabled to note the location of fishes in the water as well as submarine pockets in which fishes are in the habit of collecting and feeding.

70 In order to enable those within the cabin 8 to see down into a body of water, it is essential that the cabin 8 be darkened to a considerable extent. Therefore in order to 80 practically exclude the light from the interior of the cabin, and at the same time afford necessary ventilation for comfort, I provide the side walls and end wall of the cabin with grills 10. Each of these grills is 85 constructed in the manner best shown in Fig. 4, the same being composed of an open frame 11, and spaced deflectors 12 of cone shape in cross-section extending between opposed bars of the frame; the spaces 13 between the deflectors 12 serving for the entry and exit of air, while the arrangement of the apex of one blade within an adjoining deflector practically prevents the passage of light. At its forward end the cabin 8 is provided with a door 14 for the convenient passage of persons into and out of the cabin.

90 It will be manifest from the foregoing that while adequately ventilated, the interior of the cabin will be sufficiently dark to enable 100 those in the cabin to see plainly through the observation opening 9 and a considerable distance down in the water in which the boat is floated. It will also be appreciated that when desired a person in the cabin 8 may 105 fish to advantage through the opening 9, such person being able to see the fish in the water below the cabin.

110 It is essential to good visibility through the water that the water below the observation opening 9 be smooth or quiet, and to this end I provide in combination with the

channel 7 one or more rakes 15 and a transverse fender 16 in rear of the rake or rakes; the said fender 16 being preferably of canvas and arranged in upright position in the 5 said channel 7. I prefer to employ three of the rakes 15, and I also prefer to have the foremost rake extend downwardly and forwardly from the deck 5, while the rear rakes which are connected together at 17 10 so as to be adjustable as a unit, are inclined downwardly and rearwardly from the deck; this arrangement being advantageous because it enables the rakes to better coöperate in dissipating waves. The fender 16 15 manifestly serves to render smooth or quiet the wave-bearing or rough water that reaches the portion of the channel 7 in rear of the rakes 15. It is not of the essence of my invention for the rakes 15 to be adjustable, and therefore the rakes may be fixed 20 when desired. When, however, the rakes are adjustable any conventional means as illustrated may be employed to adjustably fix the same in position.

25 At 20' in the channel 7, I provide rudders to enable a person in rear of the cabin to steer the boat, and at 21 I prefer to provide a steering disk, designed to enable a person positioned on the deck in front of the cabin 8 to steer the boat with facility.

Having described my invention, what I claim and desire to secure by Letters-Patent, is:

30 1. A boat for the purpose described having a cabin and an observation opening in the floor of the cabin to enable a person within the cabin to see down into the body of water in which the boat is floated, and also having the cabin equipped with means 40 to exclude light while permitting the passage of air.

2. A boat for the purpose described comprising a hull having spaced longitudinal

pontoons between which a longitudinal central channel is formed that is open at both 45 ends and also having a deck fixed to and extending between the pontoons and above the channel and provided with an observation opening, and a cabin superimposed upon the deck, over the observation opening, 50 and having means to permit the passage of air while excluding light; the said channel being equipped in front of the observation opening with a transverse rake to break up waves, and a transverse upright fender disposed in rear of said rake. 55

3. A boat for the purpose described comprising a hull having a longitudinal channel at its under side open at both ends and also having an observation opening above 60 and in communication with the channel and a cabin above and in communication with said opening and equipped for the passage of air and the exclusion of light, and means arranged in the channel and in front of the 65 observation opening to eliminate waves and rough water at the surface.

4. A boat for the purpose described having at its under side a longitudinal channel open at its ends and an observation opening 70 above and in communication with said channel and a cabin above and in communication with said opening and provided with ventilation-affording and light-excluding means, an upright transverse fender arranged in the upper portion of the channel in advance of said opening, and upright transverse rakes arranged in the channel in front of said fender; the forward rake being deflected downwardly and forwardly from 75 the upper portion of the channel and the rear rake being deflected downwardly and rearwardly from the upper portion of the channel. 80

In testimony whereof I affix my signature. 85
FRANK I. STILES.
